UNITED STATES PATENT OFFICE.

JAMES L. ESTILL, OF SALEM, OHIO, ASSIGNOR TO HIMSELF AND DANIEL KOLL,
OF SAME PLACE.

IMPROVEMENT IN NUT-LOCKING DEVICES.

Specification forming part of Letters Patent No. 121,348, dated November 28, 1871.

To all whom it may concern:

Be it known that I, JAMES L. ESTILL, of Salem, in the county of Columbiana and State of Ohio, have invented certain new and useful Improvements in Lock-Nuts for Railway Rails, of which the following is a specification:

My invention relates to lock-nuts for railway rails; and it consists of a slip of tough malleable metal secured in place to perform its function for locking the nuts of screw-bolts by means of the fish-plate—that is to say, having one end of said malleable slip clamped between the fish-plate and the rail, so as to constitute a fixed point upon which said plates may be locked and unlocked with the nuts when desired. My invention further consists in bending one end of the malleable lock-plate over toward the fish-plate so as to form a lip to hold said lock-plate out from the fish-plate, thus preventing the possibility of the nuts eventually riding over the ends of the lock-plate. And my invention further consists in arranging the locking-plates so that a portion thereof will form a cushion to support the fish-plate from the sides of the rail, and thereby form a space between the two for the purpose of relieving the jar and heavy strain upon the fish-plates, and thus in a very great degree relieve the vibration of the rails upon the nuts.

The fish-plates are placed on the opposite sides of the rail, and the bolts are passed through in the usual manner.

In the accompanying drawing, Figure 1 represents a view in perspective of a portion of a railway rail, showing my improvement applied to the screw-nuts of the fish-plate thereof. Fig. 2 represents a vertical transverse section, showing the locking-plate clamped in position. Fig. 3 represents my improvement as applied to a single nut.

A slip of tough malleable sheet metal, *a*, of a width sufficient to cause its edges to come in contact with the inner adjacent sides of two nuts, *b*, when said nuts have their adjacent sides vertical, is employed for locking the nuts upon their screw-bolts. One end of this malleable sheet-metal lock-plate *a* is slipped under the fish-plate *B* and between said fish-plate and the

rail *A*, thus forming a perfect cushion for the fish-plate and keeping it from the rail. This lock-plate is of sufficient thickness at this point to fill the space between the fish-plate and the rail. The curve of the upper side of the base of the rail serves to hold the lock-plate *a* in position, when clamped by the fish-plate, against the side of the rail by screwing up the nuts, the malleable-metal lock-plate *a* being bent over between said nuts, as shown in the drawing, when the fish-plate is perfectly tight. The locking end of the plate *a* is bent over toward the fish-plate so as to form a lip, *c*, to hold said plate *a* out from the fish-plate, which prevents the nuts from eventually riding over the ends thereof, which might occur if it were flush with the fish-plate.

In addition to the advantage of using the fish-plate to clamp the lock-plate, the latter also keeps the fish-plate away from the rail a distance equal to the thickness of said malleable plate, and in this respect is very advantageous in forming a cushion, allowing the fish-plate to yield to the vibrations of the rails and thus avoid, in a very great degree, the liability of the fish-plate to be broken by severe strain and close contact with the sides of the rails. The nuts can be easily removed by straightening the bent portions of the malleable-metal slips. The intervention of the malleable-metal lock-plate between the rail and the fish-plate forms a cushion for the latter, which, in connection with the space between them, affords great relief to the fish-plate from the heavy strain and vibrations of the parts at the joints of the rails, and forms the fastening for said plate *a*, both in locking and unlocking the nuts thereby, as the plates can be bent in or out while held by their inner clamped ends.

It is obvious that the malleable-metal locking-plate may be applied to lock a single nut and be held in position by the fish-plate, as illustrated in Fig. 3 of the drawing.

Having described my invention, I claim—

1. A malleable sheet-metal slip having one end clamped by, or by and between, the fish-plate and the rail, and the other end between the nuts to be locked, as and for the purpose described.
2. The malleable-metal lock-plate intervened

between the rail and the fish-plate to cushion the latter and form a space between the rail and said fish-plate, as described.

3. The tough malleable-metal lock-plate *a*, held in position to lock and unlock the nuts by means of the fish-plate, as described.

4. The lip *c* of the malleable-metal lock-plate

for holding its nut-locking end away from the fish-plate, as and for the purpose described.

In testimony whereof I have hereunto set my hand in the presence of two witnesses.

Witnesses: JAMES L. ESTILL.

JOSEPH FAUCETT,

PETER AMBLER.
